CLAIM

The ornamental design for a USB flash drive, as shown and described in the drawings.

DESCRIPTION

FIG. 1 is a front, top and left side perspective view of the USB flash drive showing my new design.

FIG. 2 is a back, top, and right side perspective view thereof.

FIG. 3 is a front, top, and right side perspective view thereof.

FIG. 4 is a back, top, and left side perspective view thereof.

FIG. 5 is a back, top, and left side exploded perspective view thereof.

FIG. 6 is a front, top, and right side exploded perspective view thereof.

FIG. 7 is a right side view thereof.

FIG. 8 is a bottom view thereof.

FIG. 9 is a left side view thereof.

FIG. 10 is a top view thereof.

FIG. 11 is a front view thereof; and,

FIG. 12 is a back view thereof.
